United States Patent Office

Des. 217,193
Patented Apr. 14, 1970

217,193

AIRPLANE

David B. Lindsay, Jr., Box 1719, Sarasota, Fla. 33578

Filed Sept. 27, 1968, Ser. No. 13,744

Term of patent 14 years

Int. Cl. D12—07

U.S. Cl. D71—1

FIG. 1

FIG. 2

FIG. 3

FIG. 4

FIG. 1 is a perspective view of an airplane embodying my design with the landing gear shown in the lowered position;

FIG. 2 is a front elevation view thereof;

FIG. 3 is a top plan view thereof; and

FIG. 4 is a side elevation view thereof illustrating the side concealed in FIG. 1, and with the landing gear raised.

I claim:

The ornamental design for an airplane, substantially as shown.
